GREASE GUN

Ezra W. Schimpf, Marion, Kans.

Application January 5, 1953, Serial No. 329,544

6 Claims. (Cl. 222—327)

This invention relates to grease guns of the so-called portable type commonly used in applying lubricants to various parts of an automobile such, for example, as the chassis or other parts requiring lubrication from time to time.

The primary object of the present invention is to provide a generally improved grease gun which may be readily operated, easily controlled when in use, and which is of such character that it may be conveniently loaded by the operator without his being subject to direct contact with the grease when carrying out the loading operation.

To the above and other ends, the invention contemplates a cylindrical container adapted for the reception of a cartridge-like package of grease or other lubricant which may be forcibly ejected under the action of a compression spring housed within the container and adapted to be conveniently released so as to urge its associated cup-like piston forwardly and into said package where sufficient pressure is exerted on the content of the cartridge to eject the same from the gun by way of a suitable delivery tube attached to the container at its forward end and equipped with suitable control means, whereby such tube may be opened and closed, as occasion may require, to control the delivery of lubricant by way of an outlet nozzle with which the delivery tube is equipped at its forward end.

Other objects and advantages of the invention will become apparent from the following description when taken in connection with the accompanying drawings, in which

Fig. 1 is a central longitudinal sectional view showing a grease gun embodying this invention and illustrating the grease content thereof as having been partially consumed;

Fig. 2 is a fragmentary longitudinal sectional view of a control valve which is adapted to be moved from its closed position in Fig. 1 to its opened position, as shown, and by which ejection of the grease content of the cartridge may be manually controlled;

Fig. 3 is a fragmentary central longitudinal sectional view of the rear end of the gun, the cup-like piston being shown in its fully retracted position and there temporarily locked against displacement under the influence of its associated operating spring;

Fig. 4 is a fragmentary perspective view of the piston and illustrating the general shape of its associated locking lugs.

Fig. 5 is a rear view of the container as viewed from the right in Fig. 3; and

Fig. 6 is a side view of a grease cartridge adapted for use with the gun, the side wall of the cartridge being broken away to expose the grease content thereof.

The grease gun herein illustrated as embodying one form of the present invention includes a cylindrical cartridge-container 10 having at its rear end a closure cap 11 which is provided, as shown most clearly in Fig. 5, with a pair of diametrically oppositely disposed bayonet slots 12, the function of which will hereinafter more clearly appear. The forward end of the container 10 is a screw-

threaded as shown in Fig. 1 and is there provided with a removable control head indicated as a unit by the numeral 13.

As will be understood from an inspection of Fig. 1, the 5 container 10 is adapted for the reception of a grease cartridge indicated generally at 14 in Fig. 6 and there shown as including a cylindrical body 15, fabricated from a suitable material such as cardboard or the like, and having at one end a displaceable closure 16 located within 10 and relatively near the rear end of the cartridge, a marginal portion of the side wall of the cartridge being crimped or otherwise folded over the peripheral margin of the closure so as to effectively seal the cartridge at its rear end. The cartridge 14 is adapted for the reception 15 of a suitable grease or other lubricant, such as that indicated at G, and is sealed at its forward end by a disc-like closure 17, temporarily held in place, as by a suitable binding 18, adapted to be conveniently removed or torn away, as indicated in dotted lines in Fig. 6, at the time 20 the cartridge is introduced into the container 10 when conditioning the grease gun for use.

It will be understood, of course, that the cartridges 25 may be supplied commercially with any desired type of grease contained therein, so that the gun may be conveniently charged and conditioned for use with that particular type of grease which may be required for any given purpose, as when lubricating one part or another of an automobile.

Within the container 10 there is slidably carried a cup-like piston 19. The piston 19 is closed at its forward end by an end wall 20 of substantial thickness and is there provided with a peripheral groove within which is held a suitable piston ring 21 consisting of leather or any other appropriate material, the outside diameter of the piston ring being somewhat less than the inside diameter of the container 10 and of such diameter that it is adapted to snugly fit the inside diameter of the cartridge 14, as will be understood from an inspection of Fig. 1, wherein the piston is shown as having entered the rear end of the cartridge to a substantial extent and as having forwardly displaced the closure 16. Here it is to be noted that since the displaceable closure 16 snugly fits within the cartridge 14, where it normally serves to effectively retain the grease content within the cylindrical body 15, it follows that such closure when displaced and moved forwardly within said body will augment the action of the piston ring 21 in establishing an effective seal as between the piston and the inner wall of that body during such time as the piston is moved forwardly to expel the grease content of the cartridge.

50 In order that the piston 19 may be forcibly displaced forwardly of the container 10 so as to expel the grease content of the cartridge 14, there is provided a helical compression spring 22 which is of such diameter that it may be accommodated within the cylindrical side wall 55 of the piston 19, the spring being adapted to seat on or abut against the piston wall 20 which is provided with a slight recess 22 within which the forward end of the spring is so confined that it is prevented from shifting radially of the piston at its forward end. The rear end of the 60 spring abuts against the inner face of the closure cap 11, which is slightly concave in contour so that the spring is effectively retained against radially shifting at its rear end.

65 In order that the cartridge 14 may be readily introduced into the container 10, it becomes necessary of course to displace the piston 19 rearwardly against the action of the spring 22 and to the extent illustrated in Fig. 3. However, after such piston has been so displaced, it then becomes necessary to lock it in its rear-most position against the action of the spring; and to this 70 end, the side wall of the piston is provided with a pair of

diametrically oppositely disposed and rearwardly extending lug-like fingers 23 which are equipped at their outer ends with a pair of locking lugs 24 adapted to enter the bayonet slots 12 and to be thereafter so rotatably displaced as to establish an interlocking connection of the piston with the container 10 by way of the closure 11. It will be understood that once the lugs 24 have entered the bayonet slots, they are then so exposed that the operator, by thumb and finger manipulation, may so rotate the piston 19 as to establish the desired locking engagement as between said piston and the container closure cap 11. Conversely, it will be understood that the piston 19 may be released by reversely rotating the piston, whereupon the spring 22, within which energy has, of course, been stored, may then so act on the 15 piston as to forcibly move it forwardly against the grease content of the cartridge 14.

The control head 13 which is carried on the front end of the container 10 includes a closure cap 25 screw threadedly connected to the container, as shown, the peripheral skirt-like flange of the cap being provided with a bracket 26, the outer end of which is formed as a bearing 26', the function of which will hereinafter more clearly appear. Formed integrally or otherwise suitably connected to the central portion of the cap 25, is a post-like support 27 hereinafter more particularly referred to and adjacent to which is provided a feeder tube 28, which is disposed in an off-center relation to the cap 25 and provided with a central passage adapted to communicate with cartridge 14, as shown in Fig. 1, and to deliver grease forwardly from that cartridge under the action of the piston 19. The post 27 together with the feeder tube 28 serve as a support by which a delivery tube 29 is effectively held in an angular relation to the central axis of the container 10, as when the head is attached to that chamber.

The feeder tube 28 is connected at its extreme forward end to the delivery tube 29 and is there adapted to communicate with that tube so that grease entering the delivery tube 29 from the feeder tube 28 may be ejected from the delivery tube by way of an appropriate detachable nozzle 30 with which that tube is provided at its forward end.

In order to control the passage of grease from the feeder tube 28 into and through the delivery tube 29, there is provided a suitable control means indicated generally by the numeral 31. This control means includes a valve stem 32 rotatably and slidably supported within the rear end of the delivery tube 29, the extreme rear end of the valve stem 32 being slidably and rotatably supported within the bracket-bearing 26'. Normally, the valve stem 32 is positioned as shown in Fig. 1 so that its forward end overlies the passage of the feeder tube 28, whereby communication between the cartridge 14 and the delivery tube 29 is severed. In order that the valve stem 32 may be retracted so as to establish communication between the tubes 28 and 29, such stem is provided with a spiral groove 33 having a relatively steep pitch and into which projects a rivet-like stud 34 carried by the delivery tube and projecting inwardly through the wall of that tube. Thus, it will be understood that if the valve stem 32 is rotated in one direction as viewed from the rear in Fig. 1, such stem, by reason of the co-action between the stud 34 and the wall surfaces of the groove 33, will be so retracted as to establish communication between the tubes 28 and 29. When it is desired to move the stem 32 forwardly in order that communication as between the feeder tube 28 and the delivery tube 29 may be severed, it becomes necessary merely to rotate the valve stem 32 in an opposite direction.

Rotation of the valve stem 32 in either direction is facilitated through the medium of a valve operating handle 35, detachably connected to the outer end of a radial arm 36 having a hub portion 37 connected to the valve stem and serving as an abutment limiting forward

movement of the valve stem to a sufficient predetermined extent to close the outer end of the feeder tube 28, as shown in Fig. 1.

Preferably, a compression spring 38 is carried by the valve stem and is so positioned as between the bracket-bearing 26' and the hub portion 37 of the arm 36 as to exert sufficient pressure on that hub to hold the valve stem against accidental displacement which would, in turn, establish undesirable communication between the feeder tube 28 and the delivery tube 29.

Since the valve operating handle 35 is detachably connected to the arm 36 and may be of any suitable length, such handle may be conveniently employed, when the head 13 is removed, to force the piston 19 rearwardly into its latched position, as shown in Fig. 3, when it becomes necessary to conditioning the gun for use preparatory to the insertion of a grease cartridge.

Referring again to the nozzle 30, it is to be observed that such nozzle is equipped with a suitable valve 39 normally seated on the outer end of the delivery tube 29 and there held in closed position under the action of a compression spring 40, the outer end of which is confined within a slight depression formed internally of the nozzle adjacent the exit duct 41 thereof. The primary function of the valve 39 is to maintain the outer end of the delivery tube 29 closed when the gun is not in use so as to prevent possible seepage of grease from that tube into the nozzle 30. When the gun is placed in operation, the valve 39, in response to pressure exerted thereon by the lubricant within the delivery tube 29, will open against the influence of its associated spring 40 so as to permit such lubricant to be expelled by way of the nozzle 30.

Although the grease content of the cartridge 14 is subjected to the action of the spring 22 at all times pursuant to the release of that spring, escape of grease from the container 10 by way of its screw threaded connection with the closure cap 25 is prevented by reason of the fact that the cartridge is provided at its forward end with an outwardly extending sealing flange 42 which is adapted to overlie the forward end of the container and there serve as a gasket when the closure cap is run down into impinging engagement therewith as shown in Figure 1.

In view of the foregoing description, it will become apparent that the grease gun herein illustrated as embodying my invention affords a convenient means by which a lubricant originally contained within an inexpensive disposable cartridge may be conveniently ejected from the gun and utilized in the carrying out of various lubricating operations, such as those which are demanded in the maintenance of motor vehicles and the like.

What is claimed is:

1. A grease gun comprising a container, a displaceable piston slidably mounted within said container, a spring acting on said piston from the rear thereof and adapted to be compressed incident to the movement of said piston rearwardly into locking position, releasable means for locking said piston in its rearmost position whereby said spring is maintained under compression so that its energy may be utilized to forwardly displace the piston incident to release of said locking means, said releasable means including a closure cap located at one end of said container and having a pair of bayonet slots formed therein and a pair of locking lugs carried by said piston and adapted to enter said bayonet slots and there cooperate with said closure to releasably retain said piston in its retracted position against the influence of said spring, a grease receptacle in the form of a cartridge disposed within said container and urging said piston rearwardly against the action of said spring, the contents of said cartridge being adapted to be subjected to the action of said piston under the influence of said spring, a control head carried by said chamber and by way of which the cartridge content may be ejected from said cartridge under the action of said spring, and manually operable control means by

which the delivery of the grease content of said cartridge may be controlled.

2. A grease gun according to claim 1, wherein said cartridge is characterized by the fact that it is provided at one end with an end wall adapted to be removed to permit the escape of the cartridge content under pressure and by the fact that its other end is closed by a wall-like section adapted to be engaged by said piston and to be moved forwardly thereof along the inner wall of said cartridge under the action of said spring.

3. A grease gun according to claim 1, wherein said control head includes a delivery tube and a feeder tube, by way of which feeder tube communication may be established as between said delivery tube and said cartridge and through which the cartridge content is adapted to be directed into said delivery tube.

4. A grease gun comprising a container, a displaceable piston slidably mounted within said container, a spring acting on said piston from the rear thereof and adapted to be compressed incident to the movement of said piston rearwardly into locking position, releasable means for locking said piston in its rearmost position whereby said spring is maintained under compression so that its energy may be utilized to forwardly displace the piston incident to release of said locking means, said releasable means including a closure cap located at one end of said container and having a pair of bayonet slots formed therein and a pair of locking lugs carried by said piston and adapted to enter said bayonet slots and there cooperate with said closure to releasably retain said piston in its retracted position against the influence of said spring, a grease receptacle in the form of a cartridge disposed within said container and the contents of which are adapted to be subjected to the action of said piston under the influence of said spring, a control head carried by said chamber and by way of which the cartridge content may be ejected from said cartridge under the action of said

spring, said head including a delivery tube and a feeder tube, by way of which feeder tube communication may be established as between said delivery tube and said cartridge and through which the cartridge content is adapted to be directed into said delivery tube, manually operable control means by which the delivery of the grease content of said cartridge may be controlled, said control means including a valve stem carried within said delivery tube and there adapted to respectively establish and sever communication as between said feeder tube and said delivery tube, said valve stem being provided with a spiral groove and said delivery tube being provided with a lug-like stud having one end located within said groove whereby rotation of said stem will, in turn, effect longitudinal displacement of said valve stem with reference to said delivery tube, and means associated with said valve stem for facilitating rotation thereof.

5. A grease gun according to claim 4, wherein pressure means in the form of a compressible spring is associated with said valve stem and adapted to coact therewith to normally retain said valve stem in closed position.

6. A grease gun according to claim 4, wherein said cartridge is provided at one end with an outwardly extending sealing flange impinging held by and between said head and said container and there serving as a gasket.
